UNITED STATES PATENT OFFICE.

PETER PAUL AIELLO, OF SHOREWOOD, WISCONSIN.

DESIGN FOR AN ITALIAN SMOKING CHAIR.

Application filed May 6, 1929. Serial No. 31,125. Term of patent 14 years.

To all whom it may concern:

Be it known that I, PETER PAUL AIELLO, a citizen of Italy, residing at Shorewood, in the county of Milwaukee and State of Wisconsin, have invented a new, original, and ornamental Design for an Italian Smoking Chair, of which the following is a specification, reference being had to the accompanying drawing, forming part thereof.

In the drawing—

I claim:

The ornamental design for an Italian smoking chair as shown.

PETER PAUL AIELLO.
